DESIGN FOR A KNIFE

Ezra G. Waterman, Brooklyn, N. Y., assignor to E. G. Waterman & Company, New York, N. Y., a copartnership composed of Ezra G. Waterman and Frank J. Brigant

Application November 4, 1944, Serial No. 116,144

Term of patent 14 years

(Cl. D22—3)

To all whom it may concern:

Be it known that I, Ezra G. Waterman, a citizen of the United States, residing at 2175 E. 33rd St., Brooklyn, N. Y., in the county of Kings and State of New York, have invented a new, original, and ornamental Design for a Knife, of which the following is a specification, reference being had to the accompanying drawing forming a part thereof, wherein:

Fig. 1 is a top plan view of a knife showing my new design;

Fig. 2 is a side elevational view; and

Fig. 3 is an end view thereof taken from the handle end.

I claim:

The ornamental design for a knife, as shown.

EZRA G. WATERMAN.
